UNITED STATES PATENT OFFICE.

WILLIAM L. CLOUSE, OF TIFFIN, OHIO, ASSIGNOR TO THE NATIONAL MACHINERY CO., OF TIFFIN, OHIO.

HEADING-SLIDE FOR FORGING-MACHINES.

1,297,101.

Specification of Letters Patent. Patented Mar. 11, 1919.

Application filed October 14, 1918. Serial No. 257,964.

To all whom it may concern:

Be it known that I, WILLIAM L. CLOUSE, a citizen of the United States, residing at Tiffin, in the county of Seneca and State of Ohio, have invented a new and useful Heading-Slide for Forging-Machines, of which the following is a specification.

This invention relates to bolt heading and forging machines and has for an object the reduction in the size of machines of this character without shortening the heading slide, so that the advantages of a long slide remain present and the efficiency of the machine is not reduced.

Another object is to provide a heading slide which bridges the operating shaft and its connections therewith, thereby enabling the slide to be supported beyond both sides of the shaft.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention as set forth in the appended claims.

In the accompanying drawings the preferred form of the invention has been shown.

In said drawings

Figure 1 is a plan view of a portion of a bolt heading and forging machine having the improved heading slide thereon.

Fig. 2 is a vertical section through the slide and adjacent parts.

Referring to the figures by characters of reference, 1 designates the frame of the machine provided with the usual channel or guideway 2 for the heading slide, there being dies 3 at one end of the channel, a die slide 4, and means for operating the die slide, all of which constitutes no part of the present invention.

The operating shaft 5 extends across the channel 2 and has an eccentric 6 or the like for operating an arm 7. The heading slide

8 is mounted in the channel 2 and bears on the bottom thereof at opposite sides of the shaft, there being an intermediate arched portion of the slide which bridges over the shaft 5 and arm 7, as shown at 9. The arm 55 is connected to the slide at the front portion of the arch and as indicated at 10 and the arch is so proportioned as to allow the arm and its connections to work freely below the arch with the result that, as the 60 shaft 5 rotates, the slide will be reciprocated within the channel 2. Heretofore the shaft has been located back of the path of movement of the slide and the pitman or the like has been interposed between the 65 shaft and the slide. This has required the use of a frame 1 of objectionable length. With the present arrangement, however, the slide can be made longer than ordinarily and, at the same time, the length of the 70 frame can be reduced. By increasing the length of the heading slide better alinement of the slide with the work is obtained and the articles produced are correspondingly improved.

What is claimed is:—

1. In a bolt heading and forging machine a heading slide having an intermediate offset portion; an operating shaft extending transversely of the slide and past the offset 80 portion, and means housed by said offset portion for transmitting motion from the shaft to the slide.

2. In a bolt heading and forging machine the combination with a frame having a 85 guideway, of a heading slide mounted on the guideway, an operating shaft, said slide bearing on the guideway at opposite sides of the shaft and extending across the shaft, and means connecting the shaft with an intermediate portion of the slide for operating the slide.

In testimony that I claim the foregoing as my own, I have hereto affixed my signature in the presence of two witnesses.

WILLIAM L. CLOUSE.
